FIG. 6.

UNITED STATES PATENT OFFICE.

LYMAN R. ROBERTS, OF RUTHERFORD, NEW JERSEY, ASSIGNOR TO UNDERWOOD TYPE-WRITER COMPANY, OF NEW YORK, N. Y., A CORPORATION OF DELAWARE.

MACHINE FOR PERFORATING MASTER-SHEETS FOR TYPE-WRITER OPERATORS.

1,160,101.

Specification of Letters Patent.

Patented Nov. 9, 1915.

Application filed August 12, 1911. Serial No. 643,686.

To all whom it may concern:

Be it known that I, LYMAN R. ROBERTS, a citizen of the United States, residing in Rutherford, in the county of Bergen and 5 State of New Jersey, have invented certain new and useful Improvements in Machines for Perforating Master-Sheets for Type-Writer Operators, of which the following is a specification.

10 This invention relates to keyboard machines for punching master sheets, cards, etc., for use especially in operating typewriting machines. A punching machine of this class is illustrated in United States 15 Patent No. 953,180, granted to Roberts and Davis March 29, 1910. In the machine shown in said patent, the power for operating the punches is supplied by the fingers of the operator.

20 One object of the present invention is to provide a machine which will punch very heavy paper or cards, without unduly fatiguing the operator. To this end, I have provided a power device preferably electrical for operating the punches, and have arranged a series of interponents normally in idle position, but each movable by its associated key between its associated punch and said electrical device, so that the latter 25 30 may operate the selected punch. Each key not only sets an interponent, but also closes a circuit through a magnet, whereby the electrical device is actuated. By this means very light strokes upon the keys are sufficient to punch perforations in very heavy cards, and the operator can work a long time without fatigue.

In the accompanying drawings, Figure 1 is a sectional side elevation, showing so 40 45 much of the machine illustrated in said patent as is sufficient to illustrate the present improvements; the parts being shown in normal positions. Fig. 2 illustrates a key as having set an interponent and nearly completed its stroke; the electrical circuit being not yet closed. Fig. 3 is a view similar to Fig. 2, but showing the key fully depressed and the punch operated. Fig. 4 is a front elevation showing punches, interponents, and a common hammer or actuator for said interponents. Fig. 5 is a perspective diagram of the electrical devices and connections to keys. Fig. 6 is a plan of

the keyboard and the lower portion of the machine.

55 Keys 1, corresponding to the alphabet and numeral keys of a typewriting machine, are arranged upon the front ends of levers 2, each fulcrumed between its ends at 3. The rear ends of the levers underlie a series of 60 upstanding interponents 4, the latter guided on upper and lower horizontal transverse rods 5 and 6 fixed in the frame of the machine; each interponent having an upper 65 guide slot 7 and a lower guide slot 8 engaging said rods. Above the interponents is a horizontal row of punches 9, each 70 slideable rearwardly and forwardly in a guide bracket 10, and having returning springs 11; a perforated bar or matrix 12 being 75 fixed back of the punches, and a space being left between the punches and the matrix for the passage of a sheet 13 of heavy paper or cardboard, which may be suitably supported and fed, as by means of rollers 14. 80 The paper 13 is shown as supplied from a spool 15; but it will be understood that cards may be otherwise fed to the punches.

Upon the depression of any key 1, its rear end is lifted together with the overlying interponent 4, until the latter reaches the position seen at Fig. 2 with its head 16 just in front of the associated punch 9. Further downward movement of the key brings a contact 17 on lever 2 into engagement with a contact 18, thereby closing an electrical circuit through a magnet 19 and attracting an armature 20 provided upon a rock shaft 21, which extends horizontally across the machine, and carries at its ends upright 85 90 arms 22 rigidly secured thereto and united at their upper ends by a relatively heavy bar 23, which serves as a hammer head to drive the interponent head 16 backwardly, together with the selected punch, to punch a 95 hole in the sheet 13, as at Fig. 3; an elbow 24 in the slot 7 permitting this vibration of the interponent 4. Upon the release of the key from pressure, the punch is returned by spring 11, and the same spring swings back 100 the interponent. A spring 25 returns the rock shaft 21 together with the hammer head 23 and armature 20; and an individual spring 26 returns the key lever to normal position.

105 It will be understood that the hammer

head 23 in striking swings over or above the tops of the idle interponents 4. At Fig. 6 it will be seen that the levers 2 converge between their ends, the converging portions being preferably all forward of the fulcrum bar 3, and that the width of the system of levers and punches is substantially less than the width of the keyboard.

There is one of the contacts 18 for each 10 of the keys; and these contacts are preferably provided upon the forward ends of yielding fingers 27, which are secured at their rear ends by screws 28 into a block 29 of insulating material, and press up near 15 their forward ends against an insulating support 30. The ends of the wires of the magnet 19 may connect two posts 31 and 32. A conductor 33 may extend from 31 to a horizontal main conductor in the form 20 of a bar 34 extending across the machine beneath the keys; and individual conductors 35 may extend from said bar 34 to all the contacts 17, so that the magnet circuit may be closed through 31, 33, 34, 35, 17, 18, 27, 25 and a conductor 36 which runs through a source of power 37, the latter being connected by a conductor 38 to the other post 32.

A condenser 39 to prevent sparking in the making and breaking of contacts may be 30 connected in the manner illustrated, one conductor 40 being connected by a screw 41 to a plate 42, from which all the spring fingers extend; and the other conductor 43 may be connected to a horizontal transverse 35 plate 44, the latter having individual connections 45 to the contacts 17. These individual connections may be attached to the key levers by screws 46 threaded into binding plates 47 carrying the contacts 17, the 40 binding plates being attached to insulating blocks 48 on the key levers, Fig. 5.

It will be seen that the machine may be operated rapidly and with certainty and great ease. The interponents 4 are very 45 light, and afford no appreciable resistance to the touch on the keys.

The universal hammer frame 23, 22, 21, may have two of the armature arms 20, one 50 at each side of the machine, as at Fig. 5, and the right hand arm may coöperate with a magnet 49, which is connected in parallel circuit with magnet 19 by means of conductors 50, 51. This insures a quick even blow of the hammer head 23, so as to operate the punches in the required manner at 55 all portions of the punch system.

It is to be understood that certain portions of the invention can be used with other means than the cutting punches. Master 60 sheets may be produced by the power or electrical means provided in a variety of ways, by interrupting the uniformity of a uniform sheet or card so as to produce irregularities which can be utilized to reproduce a definite sequence of actions.

Variations may be resorted to within the scope of the invention, and portions of the improvements may be used without others.

Having thus described my invention, I claim:

1. The combination with keys, of perforating means including a plurality of perforating members corresponding to said keys, actuating means, and interponents corresponding to each of said keys, said interponents supported on said keys and normally held by gravity in ineffective position and lifted by said keys into effective position between said actuating means and said perforating means, so that the perforating members corresponding to the keys can be operated by said actuating means when the keys are operated, and power means for driving said actuating means. 80

2. The combination with keys, of perforating means including a plurality of perforating members corresponding to said keys, actuating means, and interponents corresponding to each of said keys, said interponents supported on said keys and normally held by gravity in ineffective position and lifted by said keys into effective position between said actuating means and said perforating means, so that the perforating members corresponding to the keys can be operated by said actuating means when the keys are operated, and power means controlled by said keys for driving said actuating means. 90

3. The combination with perforating 100 means, of actuating means for operating said perforating means, a plurality of keys, a contact on each of said keys, electrical means for manipulating said actuating means and adapted to be connected to a 105 source of electricity, and contacting means adapted to be engaged by the individual contacts on said keys at the operation of any one of said keys, and connected to said source of electricity and said electrical means, so as to excite said electrical means on the actuation of any one of said keys. 110

4. The combination with perforating means, of actuating means for operating said perforating means, a plurality of keys, a contact on each of said keys, electrical means for driving said actuating means and adapted to be connected to a source of electricity, contacting means adapted to be engaged by the individual contacts on said keys at the operation of any one of said keys, and connected to said source of electricity and said electrical means, so as to excite said electrical means on the actuation of any one of said keys, and a series of interponents, one for each of said keys, movable individually by the corresponding keys to positions between said perforating means and said actuating means. 120

5. The combination with a series of 130

- punches, of a single actuating means for operating all of said punches, a series of interponents normally held by gravity in ineffective position, and keys to lift said interponents to operative position between said actuating means and said punches, to select individual punches to be operated by said actuating means.
6. The combination with a series of punches, of a single actuating means for operating all of said punches; a series of interponents normally held by gravity in ineffective position and movable between said actuating means and said punches to select individual punches to be operated by said actuating means, and a series of keys corresponding to each of said punches and on which said interponents are carried and lifted by the keys from their ineffective positions to their effective positions.
7. The combination with a series of punches, of a single actuating means for operating all of said punches, a series of interponents normally held by gravity in ineffective position and movable between said actuating means and said punches to select individual punches to be operated by said actuating means, a series of keys corresponding to each of said punches and on which said interponents are carried and lifted by the keys from their ineffective positions to their effective positions, and motive means for manipulating said actuating means controlled by said keys.
8. The combination with a plurality of punches, of a hammer for actuating said punches, a plurality of keys corresponding to said punches, and a plurality of interponents corresponding to said punches and said keys, intervening on the actuation of said keys between said punches and said hammer, whereby said hammer may actuate said punches individually, and guiding rods for said interponents, said interponents having slots to allow for play of said interponents relative to said guiding rods.
9. The combination with a plurality of punches, of a hammer for actuating said punches, a plurality of keys corresponding to said punches, and a plurality of interponents corresponding to said punches, and said keys intervening on the actuation of said keys between said punches and said hammer, whereby said hammer may actuate said punches individually, and guiding rods for said interponents, said interponents having slots to allow for play of said interponents relative to said guiding rods, one of said slots being in the form of an elbow, so as to allow for movement in two directions at angles to each other.
10. In a key-operated punching machine, the combination with a power driven hammer, of a punch, a spring holding said punch normally withdrawn but not suffi-
- ciently to bring it into the path of said hammer, a key lever, and an interponent normally resting on said lever out of the path of said hammer, but arranged to be raised by said lever into the path of said hammer to cause it to operate said punch, and to fall by gravity when said key lever is returned to normal position.
11. In a key-operated punching machine, the combination with an electro-magnet driving a hammer, of a punch, a spring holding said punch normally withdrawn but not sufficiently to bring it into the path of said hammer, a key lever, an interponent normally resting on said lever out of the path of said hammer, but arranged to be raised by said lever into the path of said hammer to cause it to operate said punch, and to fall by gravity when said key lever is returned to normal position, and an electric circuit closed by said key to operate said electro-magnet.
12. In a key-operated punching machine, the combination with a single power-driven hammer, of a plurality of punches to be operated thereby but spaced therefrom, a plurality of keys, one for each punch, and a key-operated interponent for each punch arranged to be lifted by the operation of its key into the path of said hammer so that said hammer operates the selected punch.
13. In a key-operated punching machine, the combination with a single power-driven hammer, of a plurality of punches to be operated thereby but spaced therefrom, a key lever for each machine key, and an interponent for each punch resting by gravity in ineffective position on its key but raised by the operation of its key into the path of said hammer so that said hammer operates the selected punch.
14. In a punching machine, the combination with a single hammer, of an electro-magnet for operating it, a plurality of keys, a punch for each key, an electric circuit closed by each key to cause said magnet to drive said hammer, a lever on which each key is mounted, and an interponent resting by gravity on each lever and arranged by the depression of its key to establish a connection between said hammer and its punch.
15. In a punching-machine, the combination with a matrix, of a series of punches normally withdrawn therefrom, a single hammer for operating said punches, a key for each punch, a lever on which each key is mounted, and an interponent resting by gravity on each key lever arranged to establish a connection between said hammer and a punch so that said hammer will operate the selected punch.
16. In a punching machine, the combination with a key lever pivoted intermediate its ends, of a key at one side of said pivot, a power operated hammer, a punch for each

- key, and an interponent resting by gravity on its key lever at the end opposite said key arranged to be raised by its key to effective position.
- 5 17. In a punching machine, the combination with a key lever pivoted intermediate its ends, of a key at one side of said pivot, an electric circuit closed by the depression of each key, a hammer operated by said electric circuit, a punch for each key, and an interponent resting by gravity on its key lever at the end opposite said key arranged to be raised by its key to effective position.
- 10 18. In a punching machine, the combination with a key lever, of a power operated hammer, a punch for each key, an interponent for each punch arranged to be operated by its key to cause said hammer to operate its punch, and a fixed guide for each 20 end of said interponent.
- 15 19. In a punching machine, the combination with a key lever, of an electric circuit closed by depression of said key, a hammer operated by said circuit, a punch for each key, an interponent resting by gravity on each key lever arranged to be raised by its key to effective position to cause said hammer to operate its punch, and a fixed guide for each end of said interponent.
- 25 20. The combination with a series of punches, of a hammer for operating all of said punches, a series of interponents normally held by gravity in ineffective position, and keys to lift said interponents to operative position between said hammer and punches to select individual punches to be operated by said hammer, and electromagnets controlled by said keys for operating said hammer.
- 30 21. In a sheet-perforating machine, the combination with a plurality of punches, of a hammer for actuating the punches, an electromagnet or magnets to drive the hammer, a plurality of keys corresponding to said punches, interponents actuated by said keys into position between the punches and hammer whereby the hammer may operate through the interponents to actuate the punches, and individual switches associated 45 with the keys and individually operated thereby, said switches controlling the circuit of the magnet or magnets for causing the actuation of the hammer when any key is operated and its individual interponent moved to operative position.
- 55 22. In a sheet-perforating machine, the combination with a series of punches, of a series of keys individual to said punches, interponents individually supported and operated by said keys, each interponent lifted by its key into operative relation to the corresponding punch when a key is depressed, a universal hammer operable through the interponents to drive the punches, and means to actuate said hammer.
- 60 23. In a sheet-perforating machine, the combination with a series of punches, of a series of keys individual to said punches, interponents individually supported and operated by said keys, each interponent lifted by its key into operative relation to the corresponding punch when a key is depressed, a universal hammer operable through the interponents to drive the punches, an electromagnet having an armature connected to 75 said hammer for actuating said hammer when the magnet is excited, and individual circuit-closers carried by the keys and each operable when its key is depressed to establish a circuit for the magnet.
- 70 24. The combination with a typewriter keyboard, including alphabetical and numeral keys, of a system of punches, one for each key, a punch-operating hammer, electrical means operable by said keys for actuating said hammer, and interponents shifted by said keys into position between the hammer and the punches.
- 80 25. The combination with a typewriter keyboard, including alphabetical and numeral keys, of levers bearing said keys, a system of punches, one for each key, a punch-operating hammer, electrical means controlled by said keys for actuating said hammer, and interponents engaging said levers to be shifted thereby into position between the hammer and the punches.
